BY Fred C. Raentzel, ATT'Y.

UNITED STATES PATENT OFFICE.

AUGUST RICKERT, OF NEWARK, NEW JERSEY.

DESIGN FOR A WATCH-CHAIN.

SPECIFICATION forming part of Design No. 21,557, dated May 24, 1892.

Application filed April 25, 1892. Serial No. 430,635. Term of patent 7 years.

To all whom it may concern.

Be it known that I, AUGUST RICKERT, a citizen of the United States, residing at Newark, county of Essex, and State of New Jersey, have invented and produced a new and original Design for Watch-Chains or other Similar Articles, of which the following is a specification, reference being had to the accompanying drawings, and to letters of reference marked thereon, which form a part of this specification.

In the drawings, Figure 1 is a face or top view of my design for a watch-chain or similar article, and Fig. 2 is a side view of the same. The views are deemed sufficient to fully illustrate my design, and the design is composed of two distinct elements to insure the beauty of the article. These consist, first, in the peculiar configuration or form of the several links intertwined to form a watch-chain or similar article, having arranged upon a substantially flat body portion of the chain a series of intertwined link portions, which form a narrower and raised structure, said structure being centrally disposed with the substantially flat portion of the chain, as will be hereinafter more fully set forth, and, sec-

ondly, in said arrangement of intertwined links to form the chain formed in a series of curves and terminating in free ends, also, as 30 will be hereinafter more fully set forth.

Referring to the accompanying drawings, *a* indicates the several links formed into a series of curves and terminating in the free ends *a'*, and these links intersect and cross 35 one another, terminating in a series of curves or convolutions of a spiral form having the free projecting ends, and the several link portions being intertwined one with another to form a centrally disposed and raised structure *b* of intersecting curves or convolutions of a spiral form, as will be seen and understood upon reference to the figures of the drawings.

What I claim is—

The design for a watch-chain or similar article, herein shown and described.

In testimony that I claim the invention set forth above I have hereunto set my hand this 22d day of April, 1892.

AUGUST RICKERT.
